UNITED STATES PATENT OFFICE.

WILLIAM SCHUTTLER, OF CHICAGO, ILLINOIS.

LOCOMOTIVE-ARCH BRICK.

1,267,912.

Specification of Letters Patent. Patented May 28, 1918.

Application filed December 28, 1917. Serial No. 209,238.

To all whom it may concern:

Be it known that I, WILLIAM SCHUTTLER, a citizen of the United States, residing at Chicago, in the county of Cook and State 5 of Illinois, have invented certain new and useful Improvements in Locomotive-Arch Brick, of which the following is a specification.

The present invention relates to a refractory brick or tile adapted for use within locomotive fire-boxes, for the purpose of forming a deflecting baffle or arch within the same.

The principal objects of the invention are 15 to provide a brick which will be easy of installation and removal, and which will be of such character as not to become readily mutilated or destroyed in shipping.

A further object of the invention is to 20 form a passage extending crosswise of the brick and from edge to edge thereof, which will serve to permit of the escape of heat from the body of the brick in a uniform manner and the entrance of cold air into 25 the body of the brick in a uniform manner, thus making a uniform heating and cooling of the brick in accordance with temperature changes.

The invention further consists in the features of construction and combination of 30 parts hereinafter described and claimed.

In the drawings:

Figure 1 is a plan view, showing a plurality of the brick of the present invention 35 in place upon water tubes, and with one of the bricks in section;

Fig. 2, a section on line 2—2 of Fig. 1 on a somewhat enlarged scale, and with a portion of the brick broken away;

Fig. 3, a section on line 3—3 of Fig. 1, with the water tube removed; and

Fig. 4, a perspective of the brick.

In the art to which the present invention relates, tiling or brick composed of fire-clay are positioned upon water tubes within a locomotive fire-box for the purpose of forming a baffle or deflecting arch so as to more efficiently mix the products of combustion and lessen the amount of smoke, as well 45

as increasing the heating efficiency. Owing to the frequent opening and closing of the fire-box door, temperature changes take place within the fire-box. It happens that these bricks, becoming heated throughout, 50 are chilled around their outer portions by the cold air coming through the open fire

door, but the center remaining hot, there is an expansion of the brick at the center and a contraction around the outside, with the result that the brick cracks. This causes it 60 to burn out more quickly and fall into the fire-box. In the present invention, a simple construction eliminates the difficulty of cracking from this cause.

Referring now to the drawings, particularly to Figs. 1 and 2, the brick are shown as mounted upon water tubes 5, which extend longitudinally of the fire-box of a locomotive in a manner well known to the art. Each of the bricks, which are designated by 70 the general numeral 6, have grooves 7 formed along opposite sides thereof to allow them to partially embrace the water tubes and rest thereon, as shown in Fig. 2.

The portion of the brick 8 which depends 75 below the tube is tapered as shown in the drawings to provide sloping walls 9, which serve to mix the gases as they traverse the bottom of the brick. Extending crosswise of the brick and in a direction crosswise of 80 the tube 5 is a passage 10 extending from edge to edge of the brick, and, as shown in the drawing, opening partially above the water tubes.

The heat transmitted to the underface of 85 the brick can pass out from the body of the brick through this passage 10 and into the fire-box, so that an even radiation of heat from all portions of the brick is obtained. When the fire-box is opened, the cold air 90 coming in on top of the brick flows through this passage 10 and is communicated to all portions of the brick, causing a uniform cooling thereof. In this manner, the center 95 of the brick does not remain in a heated condition while the outside cools, but all portions are heated and cooled in a uniform manner. This prevents an expansion of one portion of the brick and a contraction of another, which results, as previously stated, 100 in a cracking thereof.

The brick is extremely cheap and simple of manufacture and is of such form as to enable it to be readily shipped without becoming mutilated.

As shown in the drawings, there are two of the passages 10 with a central web 11 between them. This reinforces the brick so that it is strong enough to withstand the strain when suspended between the water 110 tubes. The brick can be installed and removed with the same ease as is attendant

upon baffle brick now used in locomotive fire-boxes.

I claim:

A locomotive arch brick, comprising a body configured along opposite edges to rest against water tubes, said brick having a passage formed therein extending in a direc-

tion crosswise of the brick and from side to side thereof, said passage permitting a uniform heating and cooling of all portions of 10 the brick whereby an even expansion and contraction of the entire body of the brick is obtained, substantially as described.

WILLIAM SCHUTTLER.
